UNITED STATES PATENT OFFICE.

RICHARD F. STEWART, OF BRIARCLIFF, NEW YORK.

SNOW-PLOW FOR ROAD-VEHICLES

1,215,587.

Specification of Letters Patent. Patented Feb. 13, 1917.

Application filed March 1, 1916. Serial No. 81,304.

To all whom it may concern:

Be it known that I, RICHARD F. STEWART, a citizen of the United States, residing at Briarcliff, in the State of New York, have invented certain new and useful Improvements in Snow-Plows for Road-Vehicles, of which the following is a specification, reference being had to the accompanying drawings, forming a part hereof.

This invention relates to snow plows for road vehicles and is designed, and will be described herein, with particular reference to its embodiment in motor vehicles. The invention has for its general objects to provide a plow which shall be simple in construction, inexpensive to manufacture, readily adjustable for meeting different conditions of use, and readily applicable to motor vehicles of standard construction by an unskilled operator without the use of special tools. The invention further contemplates the provision of a plow especially adaptable for the uses indicated, which shall be of such character and so constructed and arranged with respect to the vehicle, as to be free from objections which might be raised against plows constructed and arranged in ways other than those included within the scope of this invention. Sporadic attempts have been made to devise a plow which might be effective for use on a motor vehicle, but such attempts, so far as known, have been confined to the rigid mounting of a plow in front of the front wheels or the attachment of a plow either rigidly, or as a drag, to the rear of the car. Neither of these constructions is satisfactory for the reason that a plow at the front of the car can not be adjusted so as to remove snow from the roadway with that degree of nicety which is required for successful use owing to the irregularities in the road surface and the evident impracticability of permitting the plow to rest in contact with such surface, and a plow mounted in the rear in the manner suggested either fails for the same reason or becomes practically inutile by reason of its failure to move the snow from the roadway in front of the traction wheels. Other objections to such proposed constructions are the failure of the plows to track properly, thereby subjecting them to constant liability to injury through engagement with obstructions at the roadside; the unbalanced thrust exerted on one end or the other of the chassis by the pressure of the

snow, and the costliness and elaborateness of such plows, thereby rendering them fit for service only on vehicles provided therefor and driven by skilled operators. In accordance with the present invention all the principal objections to known constructions, as noted above, are eliminated by important changes in the construction, disposition and mode of use of the improved plow. In the first place, the plow is disposed under the chassis of the vehicle between the front and rear wheels and permitted to rest under its own weight on the road surface so that the snow is removed right down to the road surface in front of the traction wheels. Further, the improved plow is disposed at about that section of the car which is near the vertical axis about which it turns in changing direction so that the plow necessarily tracks at all times both as regards the front wheels and the rear wheels and so has no tendency to leave its proper alignment with respect to the wheels and the road surface to be cleaned. Again, the improved plow is so disposed with respect to the wheels of the car and the mass thereof that the thrust on the plow by the snow is absorbed by the chassis in the most effective manner and the tendency to skid eliminated to the greatest possible degree. Another feature of importance is the provision of a plow which shall, by reason of its construction, be readily convertible, so that the snow may be removed from the roadway at such portions thereof as may be desired, or most convenient, according to conditions. In the illustrated embodiment of the invention, there has been shown a plow in which the blade sections may be so disposed as to effect the clearing of the road in front of the traction wheels only, may be so combined as to cause the entire tread surface of the vehicle to be cleared by pressing the snow to opposite sides of the vehicle by reason of the opposite inclinations of the blades, or may, by a third relative disposition, be so disposed to one another as to form a continuous blade extending from one side of the chassis to the other and inclined in one direction only so as to sweep the snow to one side of the car only. In each of the dispositions described, the strains imposed by the pressure of the snow are adequately absorbed and reduced to a minimum before transmission to the chassis, by a novel frame structure to which the plows are secured. This

frame is of simple construction consisting only of a few inter-connected sections of angle pieces secured at their front ends to the front axle whereby the frame with the 5 plows is dragged and the plows rest on the road surface under their own weight and the weight of the frame and are connected at their rear ends to the rear axle of the vehicle through crossed flexible cables where- 10 by all lateral pressures on the plows and frame are absorbed yieldingly and the thrust on the chassis neutralized to the greatest extent possible. A further feature of the invention resides in the provision of 15 adjustable devices for pressing the edge of the plow into yielding engagement with the road surface, such devices taking the form in the illustrated embodiment, of a manually operable lever connected operatively 20 to the frame of the plow through a spring, the tension of which is determined by the lever. Included with these devices are means whereby the plow may be raised entirely from the road surface as may be often 25 desirable when the surface is cleared or when the car is to be backed. These and other objects of the invention will appear at greater length hereinafter in connection with a detailed description of the accompanying 30 drawings, in which—

Figure 1 is a somewhat conventional view in plan of so much of an automobile and its chassis as need be shown for an understanding of the application thereto of the im- 35 proved plow.

Fig. 2 is a view in side elevation of the car shown in Fig. 1.

Fig. 3 is a view similar to Fig. 1 but showing the sections of the improved plow dis- 40 posed in different relationship to one another for the purpose of effecting the clearing of the road surface in a somewhat different manner.

Fig. 4 are detail views of sections of the 45 improved plow.

As this description proceeds it will be evident that the improved plow is not to be limited in its application to road vehicles of any particular construction and that the section of the automobile shown in the appended drawings is merely by way of illustration of one particular use of the plow in connection with a pleasure car of common form. In this car, the front wheels *a* are 50 carried, as usual, on stub axles *a'*, pivoted, as at *a''*, to the front axle *a''*, while the rear wheels *b* may find their bearings on the rear axle which is disposed, as usual, in the casing, indicated conventionally at *b'*. The 55 traction wheels *b* receive power through the differential disposed within the housing *b''* in the manner well known. On the axles *a''* and *b'* are carried the usual springs *a''* and *b''* for the support of the chassis *c*.

60 The frame of the improved plow com-

prises rearwardly extending angle pieces *d* disposed in parallelism to one another and connected loosely to the front axle *a''* at points just outside of the front springs *a''*, as through convenient clamping means, indicated generally as U-bolts *d'* as will be evident. These parallel frame pieces *d* extend rearwardly beneath the chassis *c* and have secured adjacent their rear ends a transversely extending channel piece *d''* 75 which is of a length at least equal to the tread of the wheels *b*, for reasons which will hereinafter appear. The transverse frame member *d''* may be secured conveniently to the side frame bars *d* by suitable bolts, indicated at *d''*. At the rear ends of the side frame bars *d* are drilled holes to receive links *e* to which are connected adjustable straps *f*, respectively, to the ends of which, in turn, are secured suitable cables *g*, the ends of 80 which are attached to the casing *b'* of the rear axle, as through adjustable clamps *g'*. The improved convertible plows are made up preferably of two blade sections, such as are shown in Fig. 4, and these blade sections 85 will be so mounted on the frame as to be shiftable with relation to one another, or when required, singly detachable, in order to bring about any desired clearing action, although it should be noted here that certain features of the invention will be found 90 equally advantageous without the use of the particular blades now to be described.

The shorter blade section *h*, shown in Fig. 4, is preferably curved at both its lower and upper edges, as indicated at *h'* and *h''*, respectively, so as to effect a cutting action of the snow close to the road surface and throw the snow out to one side of the blade and prevent it from being scattered over the car body and the cleared road surface. A blade section, such as is indicated at *h*, is mounted in front of each of the traction wheels *b* by means of bolts *d''* and *d'''* passing through the respective side frame members *d* and the transversely extending frame member *d''*, whereby the short blade sections are placed in inclined positions and in such relation to the traction wheels as to clear effectively a track way therefor and permit the car to be driven forward without hindrance. Each of the sections *h* is preferably braced at the rear of its lower cutting edge by means of a strut *i* bolted to its rear side near its lower edge and engaged with the bolt *d''* of the frame pieces *d*, *d''*, heretofore referred to. This inclined strut *i* maintains the blades *h* in their intended positions against the pressures exerted thereon and, where these short blade sections are slightly dished, as will 110 oftentimes be desirable, these struts prevent the lower cutting edge from being forced rearwardly. The two blade sections *h*, described, will oftentimes satisfy a need of the motorist for plows which will clear paths for the 115 120 125 130

traction wheels and permit the car to be run without hindrance over roads on which snow is newly fallen. Under these circumstances, the motorist does not desire to clean the road surface, as such, but merely to guard himself against the danger and annoyance of stalling.

Where it is desired to use the vehicle for clearing at least so much of the road surface as the tread of the car spans, the driver may attach the short blade sections k to the fixed sections h , as through bolts k' , provided for the purpose and these oppositely inclined sections k may be secured together along their front abutting edges by means of bolts k'' . As shown in Fig. 1, the front vertical edges of these plow sections k may be flanged, as at k^3 , so as to afford firm contacting surfaces intended to be maintained in snug engagement by securing bolts k^4 . When the improved convertible plow has its blade sections so disposed as to form the oppositely tapered clearing faces shown in Fig. 1, the snow in the road will be forced to opposite sides of the car and thrown clear of it by the curvatures of the small sections h . This form of plow will be useful in clearing the streets of municipalities, and especially so where only a single track way need be opened. Since the short sections h project beyond the side faces of the traction wheels b it will be evident that the plow shown in Fig. 1 clears a road surface of greater width than the tread of the vehicle.

In Fig. 3, the improved plow has had its sections mounted in still other relations to one another. Here, one of the inclined sections k is secured to its shorter fixed section h through bolts which pass through the bolt holes k^5 adjacent the inner edge of the section h and bolt holes k^6 adjacent the outer edge of the section h . By this disposition, the blade k is caused to span the frame members d and is secured to the opposite frame member by passing one of the bolts k^2 through the vertical flange k^3 which is now placed in engagement with the side of the angle piece d . As shown in Fig. 3, the other inclined plow section k has its front vertical edge secured to the extended blade h adjacent its mid-section, by means of suitably curved bolts k^5 passing through the vertical flange k^3 on the front edge of said inclined section k and through bolt holes k^6 in the extended blade section. It should be remarked that when the blade sections k are mounted in their normal inclined relationship, as shown in Fig. 1, the holes k^6 and k^5 in the sections k and h , respectively, receive the bolts k' . The disposition of sections shown in Fig. 3 is especially useful where, in cleaning the road surface it is desired that the snow be thrown out at one side of the car only so that, when a wider track is to be cleared, it will not be necessary to remove

any snow theretofore shifted. Again, as it is quite evident that either one of the blades k may be extended in the manner just described, so as to cause the snow to be forced to either the right side of the car or to the left side, by making two trips with the car over the same road and changing the relative disposition of the blades, a road surface of a width double that of the tread of the car may be readily cleared without any difficulty. The advantage of this is particularly great when, as is often the case, the surface to be cleared is found on a hill side so that it is impracticable to run the car for the clearing operation in but one direction.

From the description given it will be evident that no matter what the relative disposition of sections may be, great advantages are to be realized in all of the snow removal where the improved frame for the plow is employed and this frame is mounted in the stated relation to the car. The plow always rests on the surface of the road under its own weight and is dragged along the road by the parallel frame members d which are loosely connected at their front ends to the front axle a^2 . So far as possible, then, the pull on the plow for the removal of the snow is exerted thereon in directions parallel to the impelling direction of the traction wheels. When only the two short sections k are employed, or when the two long inclined sections k are used in substantially the relation to each other shown in Fig. 1, the pressure of the snow on the oppositely inclined faces of these sections will be balanced so that no lateral strains are imposed on the frame members d or the chassis of the vehicle. Accordingly, no tendency for the car to skid is found. And this is true in the present construction, even though the vehicle be changing direction. It is important that the plow should be mounted between the front and rear wheels and under the chassis so that it is always at about the dead center of the chassis when the latter is being turned. The improved plow always drags, both with respect to the front wheels and to the rear wheels, so that there is never a tendency for it to move outwardly to one side or the other of the chassis, as would be the case were the plow disposed in advance of the front wheels or to the rear of the rear wheels. There is only one condition of operation under which lateral strains will be imposed on the carrying frame of the plow sections, and that is when one of the sections k is extended, as shown in Fig. 3, to form a continuous inclined plow from side to side of the chassis. In this case the bulk of the snow will be thrust to the right of the car so that its reaction on the inclined surface of the blade will tend to thrust the frame members d and the chassis to the left. This tendency is counteracted to the greatest de-

gree possible, by the improved construction, by connecting the rear ends of the frame members *d* by the crossed flexible cables *g* to the rear axle *b'*, so that all such strains will be absorbed equally through the front and rear axles and the entire mass of the car will uniformly resist these lateral strains and prevent the car from skidding. With the plow disposed to the front or rear of the car, the thrust of the snow would be given a leverage by which the chassis might be readily turned aside. In the improved construction, no such leverage is afforded and the frictional engagement of the four wheels with the road surface is brought to bear uniformly on the plow to the end that the thrust thereon by the snow may be successfully met and the car be held to its course. It should be noted that the straps *f* as well as the clamps *g'* give an adjustment of the cables *g*, whereby that degree of lateral play which is always desirable may be readily provided no matter what the wheel base of the particular car to which the plow is applied.

While it has been stated herein that the improved plow is formed as a drag and is adapted to rest on the surface of the road under its own weight so as to scrape the road surface clear and adapt itself automatically to irregularities, a feature of importance resides in the provision of yielding devices for bringing pressure to bear on the frame so as to force the scraping edge of the plow into engagement with the road surface under an adjustable pressure, the extent of which may be regulated according to conditions. Various devices for accomplishing this end may be employed as will be evident to one skilled in the art, but a convenient control is shown in the accompanying drawings. There is provided a transversely extending rock shaft *l* journaled in removable bearings *m* which may conveniently be attached to the underside of the running boards *n* of the car. On the rock shaft is fixed a hand lever *m'* which extends upwardly to a position within easy reach of the driver of the car, this hand lever *m'* being arranged to move over the face of a notched quadrant *o* whereby the lever may be maintained releasably in any one of several positions, for a purpose which will appear. On the rock shaft *l* are fixed arms *m²* on the ends of which are pivoted vertically disposed studs *m³* adapted to extend through guide openings formed therefor in the rearwardly extending frame members *d* of the plow. Operatively interposed between the frame members *d* and the respective arms *m²* are suitable springs *p*, the pressures of which tend always to force the scraping edge of the plow into firm engagement with the road surface. On the free ends of the guide studs *m³* are fixed nuts *m⁴* whereby when the studs

are raised a sufficient distance the nuts will engage the side frame members *d* and, upon continued movement of the studs *m³*, serve to lift the frame members with the plow upwardly and disengage the scraping edge of the plow from the road surface, as will be desirable when the plow is not to be used, or when the car is to be backed. From the description given, it will be evident that the operator may readily manipulate the hand lever *m'* so as to adjust the degree of tension of the springs *p* and thereby bring about a greater or less yielding pressure on the plows as may be desirable according to conditions. Again, he may relieve the plow entirely of the spring pressure by raising the studs *m³* to a point where their nuts *m⁴* engage the frame pieces *d*.

Changes in the details of construction of the parts described and rearrangements of the elements will suggest themselves to the skilled mechanic, but all such changes and rearrangements are to be deemed within the scope of this invention provided the advantages described are retained by the employment of means which fall within the scope of the appended claims.

I claim as my invention:

1. A convertible snow plow for road vehicles having traction wheels comprising a frame and four blade sections, two of which are spaced from each other and are mounted on the frame directly in front of the traction wheels, and the other two of which are attachable to the first named blades and to each other at their free edges to form a continuous plow.

2. A convertible snow plow for road vehicles having traction wheels comprising a frame and four blade sections, two of which are spaced from each other and are mounted in oppositely inclined positions on the frame directly in front of the traction wheels, and the other two of which are attachable to the first named blades, respectively, and to each other, at their free edges to form a continuous plow under the vehicle having oppositely inclined symmetrical faces.

3. A convertible snow plow for road vehicles having traction wheels comprising a frame and four blade sections, two of which are spaced from each other and are mounted in oppositely inclined positions on the frame directly in front of the traction wheels, and the other two of which are attachable to the first named blades, respectively, and to each other, at their free edges to form a continuous plow under the vehicle having oppositely inclined symmetrical faces, and either of the last named sections being also attachable at its free edge to the opposite side of the frame to present a continuous inclined face extending from one side of the chassis to the other.
